UNITED STATES PATENT OFFICE.

PAUL M. RAINY, OF GLEN RIDGE, NEW JERSEY, ASSIGNOR, BY MESNE ASSIGNMENTS, TO WESTERN ELECTRIC COMPANY, INCORPORATED, A CORPORATION OF NEW YORK.

TELEGRAPH SYSTEM.

1,177,271.

Specification of Letters Patent. Patented Mar. 28, 1916.

Application filed December 7, 1914. Serial No. 875,843.

To all whom it may concern:

Be it known that I, PAUL M. RAINY, a citizen of the United States, residing at Glen Ridge, in the county of Essex and State of New Jersey, have invented certain new and useful Improvements in Telegraph Systems, of which the following is a full, clear, concise, and exact description.

This invention relates to telegraph systems of the type wherein a plurality of lines terminate at a central office, and its principal objects are to provide an automatic distribution of incoming calls to idle operators' positions and prevent operators from interfering with a busy line.

To the above ends, the invention contemplates an automatic calling line finder apparatus associated with operators' positions, and so arranged that the apparatus of an idle operator's position picks up the calling line and effects the operation of signals to notify other operators that a given line is in a busy condition.

The above and other objects of the invention will be fully set forth in the following description and claims, and will be more readily understood by reference to the accompanying drawing in which the system of connections is shown diagrammatically.

At the central station C each operator designated to answer calls over branch lines is provided with a selecting mechanism adapted to begin operation upon the initiation of a call, automatically pick out the calling line and connect it to the operator's set. This mechanism comprises in part a selector switch 5 individual to an operator's set. The switch consists of a bank of contacts 6 arranged in pairs, one pair for each line served, and a rotatable arm 7. Arm 7 is provided with a pair of wipers 8 and 9 insulated from each other and adapted to be carried thereby over the bank of contacts 6. The arm is rotated at the proper time by an electromagnetically operated mechanism comprising a ratchet wheel and a pair of ratchets (not shown), an actuating magnet 15 and a holding magnet 16. Magnet 15 is rapid in its operation and follows the interruptions in its energizing circuit to move the arm 7 step-by-step in the direction of the arrow against the action of a restoring spring (not shown). Holding magnet 16, on the other hand, is slow to release after being once energized and so does not follow the interruptions of

the operating circuit, but holds its ratchet against the ratchet wheel during short intervals of no current, and thus prevents the premature return of arm 7. When the period of no current is lengthened, however, both ratchets are withdrawn and arm 7 returns to normal. One specific form of this type of selector switch is shown in a patent to J. L. McQuarrie 826,850, issued July 17, 1906. The contacts 6 of the various selector switches, which are associated with the same telegraph line, are connected together in multiple, as shown.

The wipers 8 and 9 are respectively connected to a portion 19 of a restoring switch 20 and an operator's set 25. This set comprises a key 26, resistance 27, sounder 28, condenser 29, signal 30 and a grounded battery 31, all of the usual and well-known construction. Any or all of the operators' positions provided with sets 25 and any other desired operators' positions may be provided with calling jacks 35 and associated busy signals 36. The jacks associated with the same line are connected in multiple through out the various positions, and to a front contact of an armature 37 of a transfer relay 38, and to a winding 39 of relay 38, while the corresponding signals 36 are connected in series to a grounded battery 40. The calling operator's sets comprise a plug 45, key 46, sounder 47, condenser 48, resistance 49 and a grounded battery 50.

The selector switch 5 is equipped with two contact springs 55 and 56. Spring 55 is joined through the winding of a starter relay 57 to a grounded battery 58, while spring 56 is connected to an armature 59 of relay 57. Normally spring 55 engages a contact spring 60 connected to a front contact 90 of armature 61 of relay 57 and battery 31, through signal 30 but when arm 7 takes its first step, springs 55 and 60 are separated. With arm 7 in its normal position, spring 56 is separated from a coöperating contact 100 of spring 65 which is joined to a portion 66 of restoring switch 20; but when arm 7 takes its initial step, springs 56 and 65 engage each other.

The telegraph line L extends from the central office C and may accommodate one or more branch stations 70. Each branch station is provided with the usual telegraphic apparatus consisting of a key 71, sounder 72 and condenser 73. Each line L, 110

upon reaching the central office C, passes to armature 37 of transfer relay 38. The back contact of armature 37 is connected through a winding 76 of a line relay 77 and the winding of a start control relay 78 to a grounded battery 79 and to an armature 85 of line relay 77. Relays 38 and 77 are individual to the lines L, but start control relay 78 may be common to a number of such lines by the use of multiple connections such as shown at 86. Start control relay 78 is provided with an armature 95 connected to ground through a constantly rotating interrupter 96. The coöperating front contact of armature 95 is joined to the tongue 97 of a manual transfer switch. This tongue plays between contacts 98 and 100, normally in engagement with contact 98 but adapted, when an operator is to be absent from her position, to be moved to engage contact 100 instead. The transfer of the tongue 97 breaks a normal circuit for current made intermittent by interrupter 96 when relay 78 is energized and extends a new circuit to the next operator's position over an extended starter wire 101. An arrester and holding relay 105 having two windings 106 and 107 is provided connected to ground and portion 19 of switch 20. Relay 105 has three armatures: armature 108 connected to starter wire 101 and adapted to coöperate with a movable front contact 109 to automatically perform the same function as the tongue 97 of the manual transfer switch; armature 115 connected to both windings 106 and 107; and armature 116 which is grounded. All of the operators' positions to which the starter wire 101 extends, are similar to the one just described except the last which has, in addition to the usual apparatus, an overflow relay 120 and an overflow signal 121 controlled thereby.

Transfer relay 38 has a holding winding 125 connected to one of the bank contacts 6 and a front contact of an armature 126 of relay 77. Relay 77 also has a holding winding 127 connected to a grounded battery 128 and to an armature 126. Armature 130 of relay 38 is connected to ground, the coöperating front contact thereof being connected to the circuit of the busy signals 36 associated with its line, while the front contact of armature 85 and the back contact of armature 130 are connected together.

When one of the branch stations 70 desires to make a call, key 71 thereof is depressed. A circuit is thereupon completed from ground, key 71, line L, armature 37 of transfer relay 38; winding 76 of line relay 77 and start control relay 78 to grounded battery 79. Relays 77 and 78 attract their armatures. Armature 126 prepares an operating and locking circuit for relay 38 and a locking circuit for relay 77 through windings 125 and 127 to contact 6, armature 85

completes a locking circuit for relays 77 and 78 from battery 79 through armature 130. The attraction of armature 95 closes a circuit from ground through interrupter 96, tongue 97, contacts 98 and 109, springs 60 and 55 and starter relay 57 to grounded battery 58. The first impulse causes relay 57 to pull up its armatures, whereupon a locking circuit is prepared therefor by armature 56 to be completed to switch 20 when springs 56 and 65 engage upon the first step of arm 7. Armature 61 closes a circuit for magnets 15 and 16 through interrupter 96, armature 95 and front contact of relay 79, tongue 97 and contact 98 and armature 109 of relay 105 to battery 110 and arm 7 starts to rotate. The first step thereof separates springs 55 and 60, breaking the previously traced energizing circuit for relay 57; but since the same step closes springs 56 and 65, which completes the new circuit therefor, the armatures of relay 57 remain attracted. The rotation continues until wipers 8 and 9 engage the pair of contacts 6 associated with the calling line L, whereupon a circuit is completed from grounded battery 128, winding 127 and armature 126 of relay 77, winding 125 of relay 38, contact 6, wiper 8, portion 19 of switch 20, and windings 107 and 106 of relay 105 to ground. Relays 38 and 105 are thereupon energized. Armature 37 of relay 38 removes line L from line relay 77 and extends it through contact 6 and wiper 9 to operator's set 25. Armature 130 provides a ground for battery 40 through the busy signals 36 which notify all operators before whom they are placed that the corresponding line is in use. The attraction of the armatures of relay 105 performs the following functions: Armature 108 breaks the interrupter circuit for magnets 15 and 16 and transfers it to the next operator's position; armature 115 completes a holding circuit for relays 105, 38 and 77 from ground through winding 106, switch 20, wiper 8, contact 6, winding 125, armature 126 and winding 127 to grounded battery 128; and armature 116 provides a holding circuit for magnets 15 and 16 and causes the display of signal 30 by current from battery 31. The operator is thus notified that she is wanted. Telegraphic conversation may now take place between the branch station 70 and the operator, and when completed the operator manipulates switch 20. This opens both portions 19 and 66, breaking the circuit for relays 105, 38 and 77 and relay 57 respectively. Magnets 15 and 16 are thereupon deenergized and arm 7 returns to normal. The deenergization of relays 105, 38 and 77 allows all of their armatures to be retracted, those associated with relay 77 breaking their contacts before those of relay 38 engage their back contacts, and all of

the apparatus is again in normal position ready to receive a call.

A call coming in on a second line while the first selector switch is still occupied with a call on the first line will, because of the action of relay 105, pass to the second selector mechanism over the extended starter wire 101. The second selector switch and its associated apparatus will thereupon pick up the calling line, as hereinbefore described. If all of the operators are busy, so that the relay 105 of the last position is energized, overflow relay 120 is connected through the various armatures and contacts 108 and 109 and starter wire 101 to the front contact of relay 78. In this event another call originating over a telegraph line, resulting in the energization of relay 78, provides a ground for this circuit 20 through the interrupter 96, and relay 120 pulls up its armature. Overflow signal 121 thereupon becomes active, notifying the operators that a call has come in without finding an idle operator.

In case an operator provided with one of the calling sets desires to make a connection with a line, plug 45 is inserted in jack 35, whereupon relay 38 is energized by current from battery 50. Relay 38 thereupon pulls up its armatures, armature 37 connecting the line L, corresponding to jack 35, directly to the calling set, and armature 130 providing a ground connection for the corresponding busy signals 36, whereupon all other operators, as in the case of an incoming call, are notified that the line is in use. Upon the completion of the telegraphic conversation, plug 45 is withdrawn, breaking the circuit for relay 38, whereupon all 40 of the apparatus returns to a normal condition.

The invention claimed is:

1. In a telegraph system, the combination of a plurality of selecting mechanisms at a central office, telegraph lines extending to the central office and there adapted to be connected to one of a plurality of said mechanisms, means for initiating the operation of one of said mechanisms to connect

an idle operator's position to a calling line, 50 a plurality of circuit connecting jacks and busy signals for each said line, an electro-responsive device for each said line for displaying all of said signals associated with a busy line, and circuit connections controlled through a calling line or a said jack for effecting the actuation of a said device. 55

2. In a telegraph system, the combination of a plurality of telegraph lines extending to a central office, a plurality of calling jacks and busy signals associated with each said line and located before a plurality of operators' positions, an automatic selector switch associated with each of a plurality of operators' positions, means for causing said switches to connect an operator's position with one of said lines upon the initiation of a call, electroresponsive devices for causing the operation of all of said signals associated with a busy line, circuit connections controlled through a calling line or a said jack for effecting the operation of said devices, and means for producing an overflow signal when all of the switches associated with one of said lines are busy 75 when a call is initiated.

3. In a call distributing system the combination of a plurality of lines extending to a central office, a plurality of selector switches each adapted to be associated with some of said lines, means individual to said lines to cause one of said switches to connect with a corresponding line, a control extending device associated with each said switch and which when a corresponding 85 switch is busy automatically associates said means with another of said switches, and an overflow signal associated with a number of said switches and thereby caused to be placed under the control of one or more of 90 said lines.

In witness whereof, I hereunto subscribe my name this 5th day of December A. D., 1914.

PAUL M. RAINES.
